his ATTORNEYS.

UNITED STATES PATENT OFFICE.

RICHARD F. BEAMER, OF SAN FRANCISCO, CALIFORNIA.

GOLF CLUB.

Application filed October 18, 1923. Serial No. 595,498.

The invention relates to golf clubs and particularly to putters.

An object of the invention is to provide a putter which will increase the accuracy and precision of putting.

The invention possesses other advantageous features, some of which, with the foregoing, will be set forth at length in the following specification where I shall outline in full that form of the invention which I have selected for illustration in the drawings accompanying and forming part of the present specification.

In said drawings:

15 Fig. 1 is a perspective view of a putter embodying my invention.

Fig. 2 is a plan view of the putter showing the relative size of its striking face with relation to a golf ball.

20 Fig. 3 is a front elevation of the putter.

A putter, more than any other golf club, is an instrument of accuracy and precision, since it is used to roll the ball for short distances only and is moved through a small 25 arc in striking the ball. Putters heretofore have been provided with large striking surfaces, in many instances, larger than the striking surfaces of drivers and brassies which are swung through a large arc in 30 striking the ball. Greater accuracy in putting can be attained by the use of a small striking space on the putter which compels the player to cause the striking face to contact with the ball at substantially the point 35 on the striking face for every stroke. This will insure uniform putting which is conducive to accuracy and precision.

In accordance with my invention I form the head 2 of the putter with a striking face 3 which is not larger in area than the cross-sectional area of the standard golf ball. This striking face 3 may be smaller in area than the cross-sectional area of the standard golf ball or it may be equal in area. The 45 striking face 3 is preferably made circular in form, but that is not essential. Thus the striking face will appear to the user as not being greater in width than the diameter of a regular golf ball. The head is preferably 50 provided with a flat upper surface 4 and a flat sole 5 and the striking face preferably

extends across the front of the head from the upper surface to the sole. The sole plate is made flat so that the head is capable of contacting with the ground along a line substantially equal in length to the width of the head and parallel to the plane of the striking face. In order to further increase the accuracy of putting and to position the striking face 3 at a right angle to the line 55 between the center of the ball and the cup in the green, the side faces 6 of the head preferably converge toward the striking face so that the head of the club is shaped somewhat in the form of a blunt arrowhead. 60 This enables the player to more accurately position the club and to more accurately judge the line of swing of the club to put the ball into the cup. In Figure 2, I have shown a golf ball 7 of slightly larger cross-sectional area than the area of the striking face 3 disposed in front of the club head. 65 The club head may be made of wood or metal and is properly weighted and balanced to secure the desired result. The 70 handle socket 8 preferably extends at an acute angle from the upper face 4 in the general direction of the plane of the face 3; so that it will not interfere with the vision of the player in sighting along the line 75 from the ball to the cup, also the positioning of the handle socket 8 is such that its axis substantially intersects a line normally 80 to the face 3 and thru the center thereof.

I claim:

1. A putter comprising a head which is wider than the diameter of a regular golf ball and having a striking face the area of which is not larger than the cross-sectional area of the regular golf ball and sides converging toward the striking face. 90

2. A putter comprising a head having a flat bottom, a striking face not larger in area than the cross-sectional area of the regular golf ball and sides converging toward 95 said face.

3. A putter comprising a head having a flat bottom, a striking face not larger in area than the cross-sectional area of the regular golf ball, a flat back wider than the 100 diameter of the golf ball and sides converging toward said face.

4. A putter comprising a head, a striking face appearing to the user as not greater in width than the diameter of a regular golf ball, said head being substantially wider than the diameter of the golf ball in the direction of the plane of the face and having a bottom surface capable of contacting

with the ground along a line substantially equal in length to the width of said head and parallel to the plane of the face.

In testimony whereof, I have hereunto set my hand.

RICHARD F. BEAMER.
